UNITED STATES PATENT OFFICE

115,981

DESIGN FOR A LOCK SET

Eugene C. Steffens, Chicago, Ill.

Application May 24, 1937, Serial No. 69,522

Term of patent 3½ years

To all whom it may concern:

Be it known that I, Eugene C. Steffens, a citizen of the United States and resident of Chicago, in the county of Cook and State of Illinois, have invented a new, original, and ornamental Design for a Lock Set, of which the following is a specification, reference being had to the accompanying drawing, forming part thereof.

In the drawing, Fig. 1 is a perspective view of the lock set in closed position; and

Fig. 2 is a perspective view of the lock set in extended position.

The dominant features of my design reside in the portions shown in solid or full lines in the drawing.

I claim:

The ornamental design for a lock set, as shown and described.

EUGENE C. STEFFENS.
